UNITED STATES PATENT OFFICE

CHARLES O. FRYE, OF EAST ORANGE, NEW JERSEY, ASSIGNOR TO NEWARK METAL SCREEN COMPANY, INC., A CORPORATION OF NEW JERSEY

COMBINED WINDOW AND SCREEN

Application filed January 24, 1930. Serial No. 423,025.

This invention relates in particular to windows having a revolving sash, for example ventilator windows in steel sash installations, one object of the invention being to provide a combined window and screen of this character embodying novel and improved features of construction which shall be simple and inexpensive in construction, easy to install and operate, have a pleasing and aesthetic appearance, effectually serve its purpose without interference with either light or air and whereby the window can be opened any extent and closed without any attention to the screen.

Another object is to provide a combined revolving window and screen wherein stationary screens are mounted on the window frame at opposite sides of the axis of swinging of the window and on the inside and outside of the window, and the revolving sash is formed on its inner and outer sides with means to maintain constant sliding contact with the edges of the both screens adjacent the axis of swinging of the window.

Other objects are to provide a construction of the character described wherein said means on the window also serves as a mid-rail for the window so that the window can be manufactured to cooperate with the screens and remain permanently installed, and the screens can be applied to and removed from the window at any time without modification, adjustment or any attention whatever to the window being required; to provide a construction whereby plain revolving windows of known type already installed can be easily and quickly remodeled or altered into a combined window and screen of the character contemplated, and to obtain other advantages and results as will be brought out by the following description.

Referring to the accompanying drawings in which corresponding and like parts are designated by the same reference character throughout the several views:

Figure 1 is a front elevation of a combined window and screen embodying my invention,

Figure 2 is a fragmentary elevation of the opposite side of the combined window and screen.

Figure 3 is a transverse vertical sectional view through structure on the line 3-3 of Figure 1.

Figure 4 is a horizontal sectional view on the line 4-4 of Figure 3.

Figure 5 is a view similar to Figure 1 showing a modified form of the invention.

Figure 6 is a fragmentary view similar to Figure 3 showing the construction illustrated in Figure 5, and

Figure 7 is a horizontal sectional view on the line 7-7 of Figure 5.

Specifically describing the embodiment of the invention illustrated in Figures 1 to 4 inclusive, the reference character A designates a window frame of any suitable construction surrounding the window opening B. A sash comprising stiles 1, top and bottom rails 2 and 3 and a mid-rail 5, is pivotally mounted intermediate its top and bottom and at one side of the frame A upon a pivot bolt 6 which passes through pivot ears 7 on the window frame A. Preferably mullions 4 are connected between the top rail and the mid-rail 5 and the bottom rail and the mid-rail 5 to support panes of glass 8. With this construction the sash B may swing about the horizontal axis 6 as indicated by dot and dash lines in Figure 3 of the drawings, so as to open and close the window.

Mounted at one side of the window and opposite the portion of the sash between the mid-rail 5 and the top rail 2 is a screen 9, and a similar screen 10 is mounted on the opposite side of the window opposite the portion of the sash between the mid-rail 5 and the bottom rail 3. These screens may be secured to the window in any suitable manner as by slidably mounting the screen 9 in vertical guides 11 and the screen 10 in a frame 12 attached to the window frame and having pivoted catches 13 overlying the screen (see Figure 1).

The mid-rail 5 is approximately T-shape in cross-section and preferably built into the sash so as to form a part thereof, and has a portion 14 at one side of the sash, preferably the inner side, substantially concentric with the axis of swinging of the sash and extending the full width of the sash. At the

other side of the sash, the mid-rail 5 is formed with a portion 15 also concentric with the axis of swinging and extending the full width of the sash. Obviously the radius of the portion 15 is greater than that of the portion 14 because of the greater distance of the outer side of the sash from the axis of swinging. These portions 14 and 15 frictionally contact with the upper side 16 of the lower screen 10 and the lower side 17 of the upper screen 9, whereby the sash may be swung upon its axis without producing any opening between the sash and the screens through which insects, dust, and the like can pass. Furthermore, the screens are not at all affected by the swinging of the sash. It is also possible to remove the screens without in any manner interfering with the mid-rail 5 of the sash, and the mid-rail is such as to 20 in no material manner interfere with the light transmitting capacity of the sash.

Between the portions 14 and 15 of the mid-rail and at opposite sides thereof are provided rabbets extending longitudinally of the mid-rail 140 to receive and support the glass panes 8 which may be secured in the rabbets in the usual way.

The invention also contemplates a construction whereby the windows of known steel sash structures may be remodeled or modified to receive screens with all of the advantages of the construction hereinbefore described. Such modification of the invention is shown in Figures 5, 6 and 7 of the drawings where reference character C represents an ordinary steel sash structure having a revolving window comprising a sash D having side rails 18 and top and bottom rails 19 and 20, the side rails being pivotally mounted between the top and bottom rails by pivot bolts 21 passing through ears 22 on the window frame. The mullions 27 at the upper portion of the sash are cut away from the central horizontal mullion 28, as are also the panes of glass 29 at the upper portion of the sash. A mid-rail 23 is inserted into the sash and comprises two sections 24 and 25. The section 24 is rabbeted at 26 to overlie the horizontal mullion 28, and at its upper edge 50 has a groove 30 to receive the panes of glass 29 and ends of the mullions 27. This section 24 is of such thickness that its outer surface is nearly flush with the outer surface of the mullions 27 and 28, as clearly shown in Figure 6. At its inner side the section 24 has a semi-cylindrical protuberance or rib 31 concentric with the axis of swinging of the sash and corresponding to the portion 14 of the mid-rail 5 hereinbefore described.

60 The section 25 is secured to the section 24 by bolts 32 and the two sections are drawn into tight engagement with the mullions 27 and 28 as the bolts are tightened. The outer surface of the section 25 is curved at 33 concentrically with the axis of swinging of the

sash and corresponds to the portion 15 of the mid-rail 5. Screens 34 and 35 may be mounted on the window exactly as are the screens 9 and 10 shown in Figures 1 to 3 inclusive, the upper edge of the lower screen 35 frictionally engaging the rib 31 while the lower edge of the upper screen 24 frictionally engages the curved surface 33.

Where the mid-rail 23 is formed of wood, preferably a sheathing 36 of sheet metal is placed over at least the outer side of the mid-rail as clearly shown in Figure 6 of the drawings, and this sheath may be secured to the mid-rail with its side edges arranged in the rabbet 36 and groove 30. This provides a smooth and weather-proof surface for the outer portions of the mid-rail.

The ends of the section 24 are rabbeted at 37 to receive the stiles 18 of the sash, and the ends of the section 35 overlie the outer sides of the stiles so that the mid-rail entirely bridges the window opening.

I am aware of such constructions as shown in Patent No. 1,223,535 dated April 24, 1917, and Patent No. 1,297,796 dated March 18, 1929, and do not desire to be understood as attempting to claim such constructions. However, while I have shown my invention as embodied in certain details of construction, it should be understood that these details may be modified and changed by those skilled in the art without departing from the spirit or scope of the invention.

Having thus described my invention, what I claim is:

1. A combined revolving window and screen, comprising a frame, a sash pivotally mounted on said frame at one side thereof and including side stiles, top and bottom rails, a horizontal mullion and a vertical mullion terminating short of said horizontal mullion, a mid-rail comprising two sections applied to opposite sides of said mullions and said stiles, means directly connected to both of said sections to clamp said sections together and to secure them to said mullions, and screens secured one upon each side of said frame and each at one side of said mid-rail, said mid-rail having two surfaces concentric with the axis of pivoting of the sash and of different radii one to maintain sliding contact with each screen in all positions of the sash.

2. A combined revolving window and screen, comprising a frame, a sash pivotally mounted on said frame at one side thereof and including side stiles, top and bottom rails, a horizontal mullion and a vertical mullion terminating short of said horizontal mullion, a mid-rail comprising two sections applied to opposite sides of said mullions and said stiles, one of said sections being rabbeted to receive said mullions, stiles and the edges of panes of glass, glass panes mounted in said sash between said stiles, rails, mid-rail and

mullions, fastening members passing through both of said sections to secure said sections together and clamp them to said mullions and stiles, and screens secured one upon each side 5 of said frame and each at one side of said mid-rail, said mid-rail having two surfaces concentric with the axis of pivoting of the sash and of different radii one to maintain sliding contact with each screen in all positions of the sash.

3. A combined revolving window and screen, comprising a frame, a sash pivotally mounted on said frame at one side thereof and including side stiles, top and bottom 15 rails, and a mid-rail approximately T-shape in cross-section connected to said side stiles and said mullions, screens secured one upon each side of said frame and each at one side of said mid-rail, said mid-rail having two 20 surfaces concentric with the axis of pivoting of the sash and of different radii one to maintain sliding contact with each screen in all positions of the sash, said mid-rail having rabbets extending longitudinally and at opposite sides thereof between said surfaces to receive and support panes of glass, and glass 25 panes secured in said sash between said stiles, rails and mid-rail.
